W. G. ROUNDS

CUTTING OR TRIMMING DEVICE

Filed July 20, 1925

UNITED STATES PATENT OFFICE.

WASHINGTON GEORGE ROUNDS, OF WOODSTOCK, CANADA.

CUTTING OR TRIMMING DEVICE.

Application filed July 20, 1925. Serial No. 44,944.

My invention relates to an improvement in a cutting or trimming device, and pertains more particularly to what is commonly known to photographers as a print trimmer.

5 The primary object of the invention is the provision of a print trimmer of a construction whereby a vast amount of time is saved in the trimming of photographic prints by reason of the fact that the first cut or trim 10 of the print is always correctly made.

Another object of the invention is the provision of a print trimmer which when in use frames the image or picture on the print in light and thereby enables the proper trimming 15 of the print.

A further object of the invention is the provision of a print trimmer of the character described which is provided with a quickly and easily adjusted gauge.

20 A still further object of the invention is the provision of a print trimming device in which the trimmings are directed into and received by a receptacle.

A still further object of the invention is 25 the provision of a print trimmer in which the trimming knife is held normally in a raised position, whereby it is ready for action or operation at all times.

Another and further object of the invention 30 is the provision of a cabinet which carries a print trimmer of the character described, which is of a construction to provide a place for receiving prints to be trimmed and a place for receiving the prints 35 after the same have been trimmed.

Other further objects, novel features of construction and improved results of the invention will appear from the following description and accompanying drawings.

40 In the drawings:

Figure 1 is a perspective view of a print trimmer constructed in accordance with the invention.

Fig. 2 is a top view of the construction appearing in Fig. 1.

Fig. 3 is a vertical sectional view of the device.

In carrying out the invention there is provided a cabinet A, which may be of any desired shape or size to meet the necessary demands to which it will be subjected. In the embodiment of the invention, as shown in the drawings, the cabinet A is of a simple and plain construction, being provided with 50 suitable legs 5 of a length to make the top 6 of the cabinet of a proper height to enable

the trimming device to be used by operators of the average stature. The cabinet A has its interior divided into two parts. The lower part of the cabinet is adapted to slidably receive a drawer 7. The upper portion of the cabinet is in communication with the drawer by reason of an open bottom 8. The top 6 of the cabinet serves as a cover for the upper top portion of the cabinet. The cabinet top 6 is provided with an opening 9, which extends from the point 10 which is adjacent one edge of the top to a point 11. Suitably mounted within the cabinet upper portion, as at 12, is an electric light 13, which is adapted to throw light against the inclined board or partition 14, which is provided with an outer white or suitable reflecting surface 15. The light is reflected upwardly, by the reflecting board, through 75 the opening 9 in the cabinet top.

Suitably mounted upon the cabinet top 6, by means of brackets 16 or the like, at its front edge and a strip 17 at its rear edge is an open frame 18. This open frame 18 carries a suitable transparent plate, preferably glass, as designated at 19. Mounted upon the rear edge of the frame 18 is a rule 20, the markings upon which face towards the front of the cabinet. 85

The trimming knife is designated at 21, and is provided with a suitable handle 22. The lower end of the knife is provided with a hub 23, which is pivotally supported upon the shaft 24, carried by the bearing 25 of 90 the bracket 26, which is suitably fastened to the strip 17 as at 27. To allow lateral movement of the knife, its shaft support 24 is provided with a common spring construction 28. By reason of the coiled spring 29, the 95 knife is normally held in a raised position.

One edge of the frame 18 is provided with a metal or cutting member 30, which is adapted to co-operate with the knife 21 when the same is pulled downwardly. As 100 clearly appears in the drawing, the cutting member 30 and the knife 21 are positioned above the opening 9 in the cabinet top.

The gauge 31 extends longitudinally below the glass top 19 and is supported upon the plate 32, the outer end 33 of which is internally threaded and supported upon the threaded gauge rod 34, which is rotatably supported as at 35 and provided at its outer end with a suitable thumb or hand screw 36. 105

The cabinet is provided at its left side with a shelf 37, and at its right side with a

shelf 38. These shelves are supported in their extended positions by the hinged brackets 39, which permit the shelves to be folded downwardly, as appears in Figs. 2 and 3 of the drawings, when desired.

Current is supplied to the electric light 13 by the conduit 40, which may have connection with a suitable current supply, such as a wall or floor plug 41.

10 A combined guard and guide 42 is provided adjacent the end of the opening 9 to assure that the cuttings are directed downwardly through the opening.

15 *Operation.*

The operation of the device is quite simple, being as follows: The electric light is connected with a suitable source of supply so that it will throw light against the reflecting surface 15, and the board 14 in turn throws this light upwardly through the opening 9, so that the glass or transparent plate is illuminated.

20 The prints being trimmed are preferably upon the shelf 37 and the gauge 31 is positioned, by means of the thumb-screw 36 the proper distance from the cutting edge 30. The distance of the gauge from the cutting edge 30 always is apparent by reason of the rule 20. It will be readily understood that the gauge is therefore positioned the proper distance from the cutting edge 30 so that an 8 x 10 or 6 x 8 print can be trimmed.

25 35 Let us assume that we are trimming a 6 x 8 print. It is desirable to trim the print on its long edges first and the gauge would therefore be positioned opposite the numeral 6 on the rule.

40 Immediately that the print is placed on the illuminated glass 19, the print will be framed in light between the edge of the opening frame 18 and the edge of the gauge 31. This framing of the print in light makes it possible to determine immediately how much of a cut it is desired to take off the edge of the print adjacent the knife or cutting edge 30, as it will be readily apparent by looking at the other edge of the print 45 how much of the print it will be necessary to cut on the second cutting. As soon as the print is properly framed in the light, the knife 21 is grasped and pulled downwardly thus cutting one long edge of the print. The print is then reversed and the cut edge is in line with the gauge with the short edge of the print abutting the rule 20. The second cut is then made.

50 60 It now remains to cut the print on its short edges and the guide is therefore moved to the numeral 8 on the rule 20 and the operation described in respect to cutting the print along its long edges is repeated until two cuttings are made at the two short edges of the print.

The severed edges of the print will fall downwardly through the opening 9 and travel down the face of the slanting board 14 and be positioned in the drawer 7.

65 As each print is trimmed, it will be deposited at the right hand side of the cabinet on the shelf 38.

70 From the foregoing it will be readily understood that the print or work to be cut is framed in light which makes it possible to always make the first cut properly. This brings about a great saving of time and saves a great many prints. When the first cut is made improperly, the print is often lost because before the cuts can be remade to properly trim the print, the print has been reduced to such a small size that it is worthless.

75 80 It will also be readily understood that the prints or work of any size can be framed in light by adjusting the gauge to the proper position.

85 90 With the use of my device, the print in reality is framed prior to trimming it to the desired size and by thus framing the print it is possible to visualize immediately the correct manner in which the print should be trimmed. This is not possible in trimmers now known upon the market.

95 100 Although there is no door shown in the drawings to close the open front of the upper space 14 of the cabinet, it will be readily understood that the completed cabinet will be provided with such a door. The door has been left off in view of the drawings so that the interior arrangement of the cabinet can be more clearly seen.

105 Having thus described my invention what I claim and desire to secure by Letters Patent is:—

110 115 1. A device for trimming photographic prints or the like, comprising a base having a transparent portion, a cutting mechanism mounted on said base and being positioned adjacent one edge of the base transparent portion, and a source of light beneath said base, whereby the work is framed in light to facilitate the proper positioning of the work to be trimmed.

120 125 2. A trimmer comprising a cabinet carrying a source of light, said cabinet having an open top, a trimming frame positioned above said open cabinet top and provided with a transparent central portion, one edge of said trimming frame being a cutting edge, a movable cutter adapted for co-operation with the cutting edge of the frame and a movable gauge below said transparent plate, whereby the work is framed between said cutting edge and said gauge.

130 3. A trimmer comprising a base having a transparent plate, a cutting edge for said base, a movable gauge below said transparent plate, a source of light beneath said plate, and a movable cutter adapted for co-

operation with the cutting edge of the base.

4. A trimmer, comprising a cabinet having an open top, a receptacle in said cabinet, a source of light beneath said open cabinet top, a trimming frame having a transparent plate mounted above said open cabinet top, one edge of said trimming frame being a cutting edge, a gauge positioned below said transparent plate and movable to and from said cutting edge, and a movable cutter adapted for co-operation with the cutting edge of the frame, whereby the work is framed in light between the gauge and the cutting edge of the frame and the severed edge of the work is delivered into the receptacle of the cabinet.

5. A trimmer, comprising a cabinet having an open top, a source of light beneath said open cabinet top, a trimming frame having a transparent plate mounted above the opening in said cabinet, one edge of the frame being a cutting edge and positioned above said cabinet opening, a movable cutter adapted for co-operation with the cutting edge of the frame, a gage below said frame and extending across the same beneath the transparent plate, said gauge being movable to and from the cutting edge of the frame, whereby the work is framed in light between the gauge and the cutting edge of the frame.

6. A photographic print trimmer, comprising a trimming frame having a transparent plate, said frame mounted upon a base having an open top, a rule positioned along the rear edge of said frame, one edge of the frame being a cutting edge, a movable cutter adapted for co-operation with the cutting edge of the frame, a gauge positioned below said transparent plate and extending across the same, means for moving the gauge to and from the cutting edge of the frame, and a source of light in said base beneath the open top thereof, whereby when the gage is set in the desired position in respect to the rule the print is framed in light between the gauge and the cutting edge of the frame.

7. A photographic print trimmer, comprising a cutting frame having a transparent plate, one edge of said frame being a shearing edge and adapted for cooperation with

a knife, a movable knife, a gauge positioned below said transparent plate and extending across the same, means to move the said gauge to and from the cutting edge of the frame, and a source of light beneath said transparent plate, whereby the print is framed in light between the gauge and the cutting edge of the frame.

8. A photographic print trimmer, comprising a cabinet having an open top and a receptacle at its base, a trimming frame having a transparent plate mounted above said open cabinet top, one edge of said frame being a cutting edge, a movable cutter adapted for co-operation with the cutting edge of the frame, a gauge positioned below said transparent plate and extending across the same, said gauge being movable to and from the cutting edge of the frame, shelves at the right and left side of the cabinet adjacent the upper end thereof, and a source of light beneath the open top of the cabinet, whereby the print is framed in light between the gauge and the cutting edge of the frame and the severed end of the print will drop downwardly through the open cabinet top into the receptacle in the bottom thereof.

9. A photographic print trimmer, comprising a trimming frame having a transparent plate, one edge of said frame being a cutting edge, a movable cutter adapted for co-operation with the cutting edge of the frame, a gauge mounted beneath said transparent plate and extending across the same, a worm-screw extending longitudinally of the frame and having engagement with one end of the gauge, means for rotating said worm-screw for moving the gauge to and from the cutting edge of the frame, and a source of light beneath the transparent plate, whereby the print is framed in light between the gauge and the cutting edge of the frame.

10. In a device of the character described, a base, a cutting mechanism mounted on said base, and a portion of said base transparent, whereby the work being operated upon by said cutting mechanism is framed in light.

In testimony whereof I hereunto affix my signature.

WASHINGTON GEORGE ROUNDS.
